DESIGN FOR A MISS'S APRON.

2106

UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A MISS'S APRON.

SPECIFICATION forming part of Design No. 18,319, dated May 15, 1888.

Application filed April 20, 1888. Serial No. 271,344. Term of patent 3½ years.

To all whom it may concern:

Be it known that I, LIZZIE ROYS, of the city, county, and State of New York, have invented and produced a new and original Design for a Pattern of a Miss's Apron; and I do hereby declare that the engraved prints accompanying this specification convey to any one accustomed to using paper patterns a clear understanding of how a garment made up by the pattern will appear.

The design shows a full skirt depending in square outline from a girdle that displays a deeply-pointed outline at the center of the

front, both top and bottom, a full ornament extending from the upper edge of the girdle at either side of the point, and broad sash-ties.

What I claim as my invention, and desire to secure by Letters Patent, is—

The design for a miss's apron, as shown in the engraved prints accompanying this specification.

LIZZIE ROYS.
